United States Patent Office

Des. 215,297
Patented Sept. 23, 1969

215,297

DATA KEYBOARD

Eugene W. Yeager, Lansdale, Pa., assignor to
Digital Information Devices Inc.

Filed Feb. 4, 1969, Ser. No. 15,625

Term of patent 14 years

Int. Cl. D14—02; D18—01

U.S. Cl. D26—5

FIG.1.

FIG.2.

FIG.3.

FIG. 4.

FIG. 5.

FIG. 6.

FIG. 1. is a top plan view from above the data keyboard of the present invention;

FIG. 2 is a front elevational view of said data keyboard;

FIG. 3 is a sectional view taken along line 3—3 of FIG. 1 in order to better illustrate the contour of the side-walls of the data keyboard;

FIG. 4 is a back elevation of the data keyboard of the present invention;

FIG. 5 is a side elevational view of the keyboard of the present invention, the opposite side being identical but in mirror image; and

FIG. 6 is a sectional view taken along line 6—6 of FIG. 2 to show contours to the front and back walls of the data keyboard.

I claim:

The ornamental design for a data keyboard, substantially as shown and described.
